UNITED STATES PATENT OFFICE.

JOHN NONNENBACHER, OF NEW YORK, N. Y.

DESIGN FOR PICTURE-FRAMES, &c.

Specification forming part of Design No. 6,959, dated October 14, 1873; application filed September 19, 1873.
[Term of Patent 3½ years.]

To all whom it may concern:

Be it known that I, JOHN NONNENBACHER, of the city, county, and State of New York, have invented a Design for Frames for Pictures, Mirrors, &c., and Cornices, of which the following is a specification:

The nature of my design is fully represented in the accompanying drawings, to which reference is made, and in which—

Figure 2 represents a face elevation, and Fig. 1 is a cross-section of the same.

a represents a portion of the molding brought well forward, and ornamented with a rusticated staff, raised and in gilt. *b* represents a plain convex molding in silver gilt. *c* represents a

recessed and concave molding, with raised ornaments, as shown, in gilt. *d* is a slightly convex molding, sunk, and with a smooth surface, and having a flat ornamentation, the ground being silvered over the gilt, leaving the ornament in bright gilt. All the remainder of the moldings, comprising the frame or cornice, are silver gilt.

What I claim as my invention is—

The design for frames, cornices, &c., as herein shown and described.

JOHN NONNENBACHER.
